CLAIM

The ornamental design for a floral wrapping material, as shown and described.

DESCRIPTION

FIG. 1 is a reduced perspective view of a floral wrapping material showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a front perspective view shown in an alternate position;
FIG. 8 is a rear perspective view thereof;
FIG. 9 is a reduced perspective view of a second alternate embodiment;
FIG. 10 is a front elevation view thereof;
FIG. 11 is a rear elevation view thereof;
FIG. 12 is a left side elevation view thereof;
FIG. 13 is a right side elevation view thereof;

FIG. 14 is a top plan view thereof;
FIG. 15 is a front perspective view shown in an alternate position;
FIG. 16 is a rear perspective view thereof; and,
FIG. 17 is a view of the pattern within the broken lines which is understood to repeat uniformly across the surface as shown in the above Figures.
